UNITED STATES PATENT OFFICE.

HENRY MILLER, OF CICERO, ILLINOIS.

FLYING-MACHINE.

1,237,364.

Specification of Letters Patent. Patented Aug. 21, 1917.

Application filed June 10, 1914, Serial No. 844,317. Renewed May 10, 1917. Serial No. 167,806.

To all whom it may concern:

Be it known that I, HENRY MILLER, a citizen of the United States, residing in Cicero, in the county of Cook and State of Illinois, have invented certain new and useful Improvements in Flying-Machines, of which the following is a specification.

The present invention relates to that class of machines for navigating the air, that are "heavier than air" and depend for their altitudinal positions (or resistance to the force of gravity) upon the action of the air upon an air plane or its equivalent, as the machine is propelled through the air.

Stated in general terms the object of the invention may be said to be the improving of flying machines of this type, and stated more particularly the object of the invention is the improving of various features or instrumentalities that are used in and about machines of this type, such, for example, as the air "plane" feature upon which depends the up lifting and up keeping (or altitudinal position) of the machine as it is propelled through the air; the steering mechanism; the propelling mechanism, the stabilizing mechanism and other features.

Still more particularly stated one of the specific objects of the invention is to completely inclose the frame work and operating parts of the machine by a sheathing so shaped and arranged that it forms in and of itself an "air plane", of sufficient horizontal extent to coöperate with the air during the forward propulsion of the machine and control its altitudinal course, subject, of course, to the steering mechanism. As to this particular feature of the invention I admit knowledge of heretofore existing flying machines of the type "lighter than air" and known as dirigible balloons or air ships, in which the sheathing of the balloon proper or the gas bag is arranged over and incloses a supporting frame, but this is not the equivalent of this instant feature of my present invention, which resides in a sheathing inclosing practically all parts of the frame and operating mechanism of the machine and shaped to form an "air plane" (functionally) adapted to do the work of the more strictly called "air plane" of machines known as aeroplanes, in which the "air planes" are located in planes above the normal horizontal level of the operating mechanism, and are of comparatively vast extent laterally with respect to the line of

travel. This comparatively vast lateral extent of the air planes has heretofore been found to be necessary in order to maintain the poise of the machine on an even-keel, (subject, of course, to the manual control of the steering mechanism) but according to the present invention the "air plane" is of greater longitudinal (the term longitudinal being here used with relation to the line of travel) than lateral extent, (an advantage of which is that it offers less resistance to the forward progress of the machine) and the poise of the machine upon an even-keel is accomplished automatically by mechanism which is herein called "stabilizer". The stabilizer has a gravitating weight so arranged that when the machine "lists" to one side or the other it (the weight) will automatically condition to operate mechanism that will counteract the listing tendency and hold the machine to an even-keel (again subject however to the manual operation of the steering mechanism).

Aeroplanes (and the present invention) may be said to relate to machines of this general class, although it is believed to be peculiar unto itself) are usually steered by "warping" the "air planes" or by auxiliary planes.

Another object of my invention is to provide what I believe to be an improved method of steering the machine, and, of course, mechanism for practically carrying this improved method into effect. To this end this specific object of the invention may be said to be the provision of means for steering the machine by discharging a current of air in such a direction that when it comes into contact with the surrounding atmosphere through which the machine is passing, it will react upon that portion of the machine from which it is discharged in such manner that it will tend to move the aforesaid portion of the machine in such direction that the machine will take the course appropriate to the manually set position of steering mechanism.

Another specific object of the invention is to provide means whereby, without changing the speed of the motor which operates the propeller, the active effect of the propeller may be controlled and regulated by the operator. The carrying out of this object, is accomplished by providing a shield, herein called a "wind brake" under the control of the operator for covering or

uncovering as much or as little of the blades of the propeller as he may desire, so that more or less of the propeller, during its rotation, may be exposed to contact with the 5 surrounding atmosphere.

Another specific object of the invention is to provide steering mechanism of such construction that the course of the machine will respond directly to the direction of the 10 movement of the hand of the operator in manipulating the steering mechanism; that is to say, when the operator desires the machine to go to the right or left he moves his hand and the steering lever which it 15 grasps to the right or left, as the case may be, and, similarly, when he desires the machine to go up or down, he moves his hand, and the steering lever which it grasps up or down, as the case may be. This may or 20 may not involve a crossing or reversal in the movement of some part or parts of the steering mechanism.

Here it may be stated, that I believe myself to be the first to provide means of any 25 form or construction for the accomplishing of the objects above briefly enumerated, and it is manifest that means of different construction, adapted to accomplish these same objects, will readily suggest themselves to 30 those skilled in the art to which the various parts of the machine, which forms the subject of the present application, relate and I therefore desire to have it understood that, excepting as hereinafter specifically 35 pointed out or claimed, my invention is not limited to mechanism of the precise construction shown in the accompanying drawings and hereinafter particularly described.

With this understood and with above 40 named and other objects in view, I here declare the present invention to consist in the various features of novelty that are hereinafter described with reference to the accompanying drawings, which are hereby 45 made a part of this specification, and in which:—

Figure 1 is a side elevation of a flying machine embodying the invention.

Fig. 2 is a view thereof partly in longitudinal section and partly in side elevation, the plane of the section being more or less irregular with a view to clearness and brevity in showing the relation of the parts.

Fig. 3 is a view thereof partly in front 55 elevation and partly in vertical transverse section, the plane of the section in this view also being more or less irregular, for a like reason.

Fig. 4 is a view which is largely idealistic 60 but intended to indicate, from in front of the machine, the courses of the various air passages of the steering mechanism.

Fig. 5 is a view thereof, mostly in plan but partly in horizontal section, again on 65 an irregular plane—or, more accurately

speaking, upon different planes, this difference being resorted to for the sake of brevity and clearness of representation.

Fig. 6 is a view partly in side elevation and partly in vertical section of the immediately manually controllable devices of 70 the steering mechanism.

Fig. 7 is a plan view of the same mechanism.

Fig. 8 is a front elevation of the principal 75 parts of the mechanism of the device that has hereinbefore been called the "stabilizer."

Fig. 9 is a plan view which, so far as it goes, is similar to Fig. 5, but which shows more particularly, on a larger scale the 80 details in construction of the steering mechanism of that form which is elected as preferred for the purposes of this application.

Figs. 9^a and 9^b are, respectively, a longitudinal and a transverse section showing details hereinafter described. 85

Fig. 10 is a view partly in plan and partly in horizontal similar to Fig. 9, but showing a modification in some parts of the steering mechanism. 90

Fig. 11 is a view of some portions thereof, partly in side elevation and partly in vertical section.

Fig. 12 is a plan view of the parts in the immediate vicinity of the operator's seat. 95

Fig. 13 is a section on the line 13—13, Fig. 5, showing on a larger scale a detail in the construction of what may appropriately be called a wind brake, for regulating the extent of contact of the propeller with the surrounding atmosphere. 100

Fig. 14 is a side elevation of details in the hand mechanism for controlling the positions of the wind brakes.

Fig. 15 is a horizontal section on a still 105 larger scale of a portion of the rear end of the machine, showing particularly the valve-mechanism for controlling the horizontal discharge of the air.

Fig. 16 is a side elevation viewed in the 110 direction of the arrow, 16, Fig. 15.

Fig. 17 is a rear elevation thereof viewed in the direction of the arrow, 17, Fig. 15.

The machine has a suitable frame, the several parts of which wherever they appear 115 in the several figures of the drawings are designated by the numeral, 1, excepting when it becomes necessary for the sake of accuracy and precision to otherwise designate them by the addition of an exponent 120 to the numeral. This frame supports, or has attached to it, all of the propelling and steering mechanism of the machine and the entire frame and practically all of said mechanism is inclosed by a sheathing, 2, 125 which, regard being had for the necessary internal space for the accommodation of the working parts and the seat, 3, for the operator is so shaped that it forms an "air plane" of very much greater longitudinal than lat-

1 sages, 12 and 12^a. This continuation-flue, 15^a, communicates with the interior chamber of a valve casing, 16, which has lateral branch flues, 17 and 17^b, which open upwardly and downwardly respectively, and its continuation-flue or passage 17^a corresponding with the continuation-flue or passage, 15^a, of the valve casing, 14, is unvalved and opens directly to the atmosphere at the 10 rear end of the machine.

15 Within the valve casing, 14, is a butterfly valve, 18, which normally occupies a horizontal plane that is central longitudinally with respect to the machine and to the natural course of the combined volumes of air passing rearward through the flues or passages, 12 and 12^a, and the continuation flue, 15^a. While this valve occupies this position the aforesaid current of air, upon 20 reaching the valve casing, 14, will not be deflected from its natural course either one way or another. Consequently, while a portion of the air may escape through the horizontally disposed lateral branches, 15 and 25 15^b, the major portion of it will pass on to and through the continuation-flue or passage, 15^a, and into the casing, 16. Upon reaching the interior of the casing, 16, in which is arranged a similar butterfly valve, 19, which 30 normally occupies a vertical plane of the axis of the continuation-flue, 15^a, the air will escape through the flue, 17^a and out to the atmosphere at the rear end of the machine, without any tendency to exert a 35 lateral pressure upon the rear end of the machine in one direction or another.

40 Thus it will be seen that so long as the butterfly valves, 18 and 19, occupy their normal central positions as above described, the force resulting from the discharge of 45 divided portions of the entire volume of air passing rearward through the flues or passage, 12 and 12^a, will be balanced against each other without any tendency to disturb the course of the machine through the air. 50 On the other hand if the position of either of the butterfly valves is changed so that it deflects the whole or a part of the volume of air laterally with respect to the machine in one direction rather than the opposite direction, the result will be a corresponding 55 lateral pressure upon the rear end of the machine which will tend to alter its longitudinal position as it passes through the air and thereby change its course. To be more specific, if the butterfly valve, 18, be placed in the position indicated by dotted lines it will intercept the entire volume of air entering the casing, 14, through its inlet opening, 12^b, and compel it to escape through the lateral branch flue, 15, which opens at the right hand side of the machine, at the same time preventing any part of said volume of air from escaping through either of the out- 60 65 let openings, 14^b or 14^c. The air issuing

from the branch flue, 15, and impinging against the surrounding atmosphere will react against the rear side of the machine with a tendency to force its rear end horizontally to the left and thereby correspondingly direct its forward end or prow to the right. In this way the horizontal course of the machine may be controlled by the operator without in any way changing its altitudinal course. On the other hand if the butterfly 70 valve, 18, is allowed to remain in its normal position as shown by full lines the altitudinal course of the machine may be controlled by the operator by similarly operating the butterfly valve, 19. If this valve be placed in the position indicated by dotted lines the entire volume of air entering the valve casing, 16, through its inlet opening, 16^b, will be deflected so that it will escape upward through the vertical branch flue, 17, with the result that a downward pressure will be exerted upon the rear end of the machine, tending to give the entire machine an upward and forward inclination, which will cause it to rise. The mechanism for operating these butterfly valves is of such construction that the operator in changing the course of the machine moves his hand naturally in the direction which he desires the machine to take. Both of the valves are controlled and operated by a single hand lever, 20, and the mechanism intervening between this lever and the valves is such that when the operator desires to direct the course of the machine to the right he moves his hand which grasps the operating lever toward the right. Similarly, when he desires to direct the course of the machine to the left he moves his hand toward the left and the same is true when he desires to go either upward or 100 downward. To these ends the hand lever, 20, is fulcrumed as at 21, between ears or lugs, 22, carried by a cylindrical fitting, 23, which is, for the most part, tubular. This fitting is maintained in a vertical position 105 so as to be capable of moving both longitudinally, up and down, and rotatively about its axis, by suitable brackets, 24, that are supported by suitable parts of the frame, 1. The tubular upper portion of the fitting, 110 23, has diametrically opposite longitudinal slots, 25, through which the lever, 20, passes and the lower end of the fitting carries a cross arm, 26, the branches of which are connected by slender rods, wires, cables, or 115 other suitable devices, 27 and 27^a, respectively, with the opposite ends of a cross lever, 28, that is secured, non-rotatively to the shaft of the valve, 18. With this arrangement it will be observed that when the 120 lever, 20, is moved toward the right it will rotate the fitting, 23, counterclock-wise as indicated by the arrow in Fig. 7. This will draw the connection, 27, forward and this in turn will move the valve, 18, to or toward 125 130

eral extent, always, however having sufficient superficial area to enable it to perform the function of uplifting and upholding the machine, in opposition to the force of gravity, as hereinbefore briefly pointed out.

This sheathing is preferably made of thin but tough and strong wood, but if desired it may be made of any other material, such as thin sheet metal (say aluminum), or sheet fabric, (say canvas, ducking, or silk) or any other material that will serve the purposes, the chief of which is to take the air pressure which results from the forward motion of the machine, converting this air pressure to the purposes of uplifting or upholding the machine, and otherwise facilitating the travel of the machine through the air, as by preventing the direct impingement of the air against the many parts of the mechanism whereby it would be broken up into a multitude of currents and countercurrents moving in incalculable directions.

So much for the sheathing, but be it remembered that it is extended longitudinally rather than laterally in order to give it the necessary superficial area to perform the functions of an air plane. The mechanism of the machine is so disposed upon opposite sides of its longitudinal center that it is normally balanced, so that it will travel on an even-keel, but in order to maintain this balance the present invention contemplates the provision of what has been hereinbefore called a stabilizer, the object of which is to counteract the effects of air currents that impinge against the machine with a tendency to throw it off of an even-keel. This stabilizer has a gravitating weight, 4, which depends from a suitably arranged support, 5, which latter may take the form of a shaft suitably supported by the frame of the machine, so that the weight, 4, will, of course, naturally and automatically tend to a pendent vertical position below its support. As shown, the weight, 4, has a vertical arm, 6, and two laterally disposed arms, 7, and 7^a, which, of course, respond to the variations in the position of the weight and control valves which later in turn, control the direction of the discharge of the stabilizing currents of air. The stabilizing of the machine involves the use of air ducts or passages, 8 and 8^a, both of which open at their forward ends at the prow or forward end of the machine and at their rear ends are deflected and open laterally, at the opposite sides of the machine as at 8^b and 8^c. When the machine is traveling upon an even-keel the air will enter the forward ends of the tubes, 8 and 8^a, and escape from their rear ends, 8^b and 8^c, laterally, without any tendency to change the altitudinal course of the machine, but when the weight, 4, of the stabilizer swings in one direction or the other, relatively to its support, 5, in response to a

canting of the machine in one direction or the other from an even-keel position, the said weight will reciprocally operate valves, 9 and 9^a, so that the air passing through the tubes, 8 and 8^a, will be diverted from its course and will be caused to be discharged, upwardly through one or the other of branches, 10 or 10^a, of the tubes and downward through one or the other branches, 11 or 11^a, of said tubes. To be more specific, if the machine cants from an even-keel in a direction which lowers its right-hand side, being the side on which the tube, 8, is located, the relative movement of the weight, 4, will naturally be toward that same side relatively and this movement of the weight will so operate the valves, 9 and 9^a, that they will deflect the course of the air passing through the tubes, 8 and 8^a, and cause it to be discharged downward through the branch, 11, on the right-hand side of the machine, and upward through the branch, 10^a, on the left-hand side of the machine, thus tending to produce upon opposite sides of the machine forces that act in opposition to the force tending to disturb the even-keel poise of the machine. It will be understood that the valves, 9 and 9^a, are of that class known as butterfly three-way valves and their connections with the weight, 4, of the stabilizer are such that they will be operated or moved simultaneously, but at the same time reciprocally in opposite directions, so that when one is moved to deflect the current of air downward, the other will be correspondingly moved to deflect its current of air upward.

In like manner the steering of the machine involves the use of two air passages, or flues, 12 and 12^a, which may be of any desired construction and which at their forward ends, open at the prow of the machine while at their rear ends, converge in the modified form of the invention shown in Figs. 10 and 11, and come together in a V-shaped fitting, 11^a, 13, which at its rear end communicates with the interior of a valve casing, 14, which latter is circular or of drum-shape. With this arrangement the entire volume of air passing through the air passages or flues, 12 and 12^a, will enter the casing, 14, which has three outlets for the air, 14^a, 14^b and 14^c, respectively and located at positions 90 degrees removed from each other, the outlet opening, 14^b, being diametrically opposite the inlet opening, 12^b, which is common to the flues or passages, 12 and 12^a. Communicating with the outlet openings, 14^a and 14^c, are air flues or passages, 15 and 15^a, which extend laterally to the right-hand and left-hand sides, respectively, of the machine, while a single flue or passage, 15^a, communicates with the outlet opening, 14^b, and forms in fact and in effect a rearward continuation common to both of the flues or pas-

the position indicated by dotted lines, with the result that the combined volume of air passing rearward through the passage, 12 and 12^a, will be discharged through the branch, 15, escaping at the right hand side of the machine, with the result already described. Naturally a movement of the hand lever, 20, in the opposite direction will produce the opposite of these results.

Within the upper tubular portion of the fitting, 23, the hand lever, 20, is fulcrumed as at 28^a, to the split or bifurcated upper end of a block, or piece, 29, to which is attached by any suitable means a ball, 30, which forms one member of a ball-and-socket joint, the socket member of which is formed at the upper end of a rod, 31, which fits within the bore of the fitting, 23, in such manner that the rod, 31, is capable of free up and down movement. The lower end of this rod is connected through the medium of a link, 32, with the radial arm, 33^a, of a bell-crank lever, 33, which latter is fulcrumed as at, 34, to a suitable part of the frame of the machine. The remaining branches of this bell-crank lever are connected with the forward ends of cords, wires, chains, cables, or other suitable connecting devices, 36 and 36^a, the rear ends of which are connected to the opposite ends of a branch lever, 37, non-rotatively secured to the shaft of the valve, 19. With this arrangement it will be seen that an upward movement of the hand lever, 20, will cause the bell-crank lever, 33, to move counterclock-wise about its pivotal support as indicated by the arrow in Fig. 6, and this in turn will draw the connection, 36, forward and cause it in turn to move the valve, 19, to or toward the position indicated by dotted lines, with the results already described.

In the modified form of the steering mechanism shown in Figs. 10 and 11, the two longitudinal air passages or flues are brought together, as already described, in a common V-shaped, fitting, 13, and while this form of the invention is believed to be wholly practicable, it is conceivable that the combining of the horizontal and latitudinal air flues or passages in the manner described may not, under some conditions, be altogether satisfactory, and hence in Figs. 1, 2, 3, 4 and 5 I have shown an arrangement which makes the steering in one direction wholly independent of the steering in the other direction. In these figures the two longitudinal air flues or passages, 12 and 12^a, are kept wholly independent of each other, throughout, and as shown more clearly in Figs. 2 and 5, the horizontal discharge branches, 15 and 15^b are in like manner functionally separate and independent of each other. These horizontal lateral branches form continuations of one of the longitudinal tubes or passages (say the tube,

12) and these branches are under the control of a butterfly valve, 18, which is constructed and operates precisely as does the butterfly valve, 18, already described with relation to Figs. 10 and 11. In like manner 70 the longitudinal tube or passage, 12^a, has upwardly and downwardly presented lateral branches, 17 and 17^b, which are under the control of a butterfly valve, 19, constructed and arranged to operate precisely 75 like the butterfly valve, 18, already described with relation to Figs. 10 and 11. It will be understood that in this preferred form of the invention the pull devices, 27 and 27^a, 36 and 36^a, are arranged precisely as are the 80 correspondingly numbered parts already described and are operated by a lever-control device like that shown in detail in Fig. 6 and shown on a small scale at 23^a in Figs. 2, 5 and 12.

The power for propelling the machine is preferably derived from two separate engines, 39 and 40, preferably of the internal combustion or explosion type, which, of course, should be of practically equal weight 90 and arranged equal distances upon opposite sides of the median longitudinal center of the machine in order to properly balance it. These engines exert their power directly upon a transverse shaft, 41, which in turn is 95 connected by any suitable gearing with the vertical shafts, 42, of propeller blades, 43, which in the instance given in the drawings have radial paddle blades, but here I desire to have it understood that my invention in 100 its broadest aspect is not limited to propeller blades of this or any other specific type, the type shown being simply illustrative of what, for the purposes of this application, I elect as preferable. Of course, the effect of these propeller blades will depend upon the extent to which they come in contact with the atmosphere through which the machine is passing, and hence by controlling the extent of this contact the effectiveness 110 of the blades may be regulated. I have, therefore, provided what is herein called a wind brake, 44, for each of the blades, this wind brake being a part under the control of the operator by which a greater or less proportion of the propeller blades may be exposed to or concealed from contact with the surrounding atmosphere. Fig. 13 shows a detail in the construction of one of these wind brakes. Of course, it will be understood that as the propeller blade revolves it will have a tendency to create a pressure within the drum, or casing, 45, in which it revolves and this pressure will have a corresponding tendency to force the wind brake 120 out of place. In order to prevent this the wind brake is provided with lugs or flanges, 46, which occupy corresponding grooves near the outer margin of the propeller blade casing, 45. The wind brakes have attached 125

to them operating rods, 47, which in turn are jointed to the ends of slide rods, 48, mounted to slide in suitably supported bearings, 49, these bearings being in turn supported by some suitable part of the frame. 5 This slide rod passes loosely through a slot in the collar, 50, and the collar itself is hinge-jointed, as at 51, to a lever arm, 52, secured to a shaft, 53, which carries a worm 10 wheel, 54, meshing with a corresponding worm, 55, secured to a shaft, 56, having a hand-wheel, 57, located within convenient reach of the operator, the construction and arrangement of this operating mechanism 15 being such that when the hand-wheel, 57, is turned, the wind brakes will be simultaneously moved through corresponding distances whereby their effectiveness in covering and uncovering the propeller blades is 20 equalized.

In addition to the automatic operation of the stabilizer, it is also under the control of the operator, to which end the weight, 4, is jointed to one end of a link, 58, the other 25 end of which is jointed to an arm 59 projecting from a shaft, 60, to which is non-rotatively secured a hand-lever, 61, located within convenient reach of the operator.

It has already been stated that the sheathing, 2, of the machine practically incloses 30 all parts of the mechanism, including the operator's seat, 3. It is, of course, necessary that provision be made for the operator to observe his course and to this end 35 look-out windows, 62, may be placed wherever convenient or desirable.

The discharge of air in one direction through one of the lateral branches of the air tubes or passages, will have a tendency to 40 create a vacuum or a current of air in the opposite direction through a communicating lateral branch and this would interfere with the proper operation of the steering mechanism, unless it be prevented. In order to 45 prevent it each of the lateral branches is provided with a cover which is operated simultaneously with and by the same mechanism as the butterfly valves are and as all of these covers are similar and are operated 50 by similar mechanism a description of but one will suffice for the purposes of this application.

Hence covers, 63 and 63^b, are provided for the horizontal branches, 15 and 15^b. Each 55 of these covers is jointed to one end of a rod, 67, having an enlarged piston-like head, 68, which slidably fits in a guide way, 69, supported by a bracket, 70, which, in turn, is suitably connected with the frame of the 60 machine. The head, 68, is cylindrical in cross section and the guideway, 69, is of similar cross sectional shape and embraces something more than 180 degrees of a circle, so that the piston head is prevented 65 from displacement from the guideway,

while at the same time it is permitted to slide freely therein. Slidably mounted upon each of the rods, 67, is a ring or collar, 66, carrying oppositely presented studs, or pins, 65, upon which is mounted the bifurcated 70 end of a link, 64, the other end of which is pivotally connected to one end of the lever, 28. Within the guideway, 69, is a spring, 73, which exerts a constant pressure upon the head, 68, with a tendency to close 75 the cover, 63, (or 63^b) as the case may be. Beyond the travel of the pins, 66^a, the guideway is a complete tube, as shown at 71, while that portion of it which is traversed by the pins, 66^a, may be either slotted for the passage of said pins, or as above suggested, 80 may be entirely cut away to the extent of less than 180 degrees.

In the operation of this mechanism the 85 extended ends of the lever 28—extending as they do beyond the points of connection with the chains, or cords, 27 and 27^a, would naturally impart to the covers, 63 and 63^b, an excess of movement and it is in order to 90 compensate for this that the sleeves, or collars, 66, are slidably mounted upon the rods, 67. In the construction shown and described, the springs, 69^a, will have a normal 95 tendency to move the covers, 63 and 63^b, in position to close the lateral branches, 15 and 15^b, the movement of the covers being arrested by stops, 63^a, which are in the form 100 of cross bars, or strips, which enter into the construction of the guiding frame, 68^c, in which the cover, 63 or 63^b, is mounted to slide.

Upon reference to Fig. 15 it will be seen that a pull upon the rod, or cord, 27, in the direction of the arrow, will shift the position of the lever, 28, and during the first 105 part of the movement of this lever, the collar, 66, will slide upon the rod, 67. When the collar, 66, comes in contact with the enlarged head, 68, the rod will be moved endwise in the direction of the arrow, thereby 110 uncovering the lateral branch, 15, and moving the parts to positions corresponding with the positions of similar parts accessory to the valve, 63^b, as these accessory parts are 115 shown in the lower portion of Fig. 15.

What I claim as new is:—

1. A flying machine having a suitable frame, an air plane and means for propelling the air plane through the atmosphere, in combination with steering mechanism, 120 said steering mechanism having unobstructed air tubes or passages the forward ends of which are open for the admission of atmospheric air, and the rear ends of which are presented laterally and are open for the 125 escape of said air and are presented horizontally in opposite directions, and also vertically, upwardly and downwardly, whereby the air discharged from said tubes or passages impinges against the surrounding 130

atmosphere and re-acts laterally upon the machine and controls its course.

2. A flying machine having a suitable frame, an air plane and means for propelling the air plane through the atmosphere in combination with steering mechanism having an air tube or passage disposed longitudinally relatively to the machine and terminating at its rear end in lateral branches having discharge ends presented horizontally and a second air tube disposed longitudinally relatively to the machine and having at its rear end lateral branches presented upwardly and downwardly, valves located at the intersection of the lateral branches of both of the aforesaid longitudinally disposed air tubes or passages for controlling the direction of the passage of air through them, and means under the control 20 of the operator for controlling said valves.

3. A flying machine having steering mechanism for controlling the course of the machine through the atmosphere, said steering mechanism having a lever under the control 25 of the operator and movable laterally both horizontally and vertically for controlling the course of the machine both horizontally and altitudinally, in combination with means for transmitting movement from said lever to the means for controlling the horizontal course of the machine, said means having a rotatable shaft to which said lever is jointed and a cross arm carried by said shaft and means for transmitting movement from 30 said lever to the mechanism for controlling the altitudinal course of the machine, said means including the shaft aforesaid, which is also capable of longitudinal movement and a T-shaped lever with the central arm 35 of which said shaft has jointed connection.

4. A steering mechanism having in combination a tubular fitting, means for supporting it so that it may be rotated, a lever fulcrumed to said fitting, a rod jointed to 45 said lever and capable of moving endwise relatively to said fitting, a cross arm carried by said fitting, tensile connections extend-

ing from the extremities of said cross arm to the valve to be manipulated, a T-shaped bell-crank lever, the central arm of which 50 is jointed to said tensile devices and extending to the valve to be operated.

5. A flying machine having air tubes or passages disposed longitudinally thereof and open at their forward and rear ends for the 55 admission and escape of air as the machine progresses in combination with a stabilizer having a pendent weight and means operated by the movement of the weight relatively to the machine for directing air currents escaping from said air tubes or passages in such directions that they will impinge against the surrounding atmosphere and react against the machine in such manner as to control its position. 60

6. A flying machine having a suitable frame, an air plane, and means for propelling the air plane through the atmosphere, in combination with steering mechanism having air tubes or passages provided with 65 discharge ends presented laterally relatively to the course of the machine, valves for controlling the flow of air through the lateral branches of the air tubes, and covers for preventing the formation of a vacuum within one lateral branch while the air is being discharged through a communicating lateral branch. 70

7. In a flying machine, having air tubes extending through it longitudinally, said 75 tubes having at their rear ends lateral branches presented in different directions, and a valve for controlling the passage of air to and through said lateral branches, of a stabilizer having a pendent weight and 80 connections between said weight and valves, whereby the position of the weight relatively to the machine determines the position of the valve. 85
